(57) **CLAIM**

The ornamental design for a manifold gauge set, as shown and described.

DESCRIPTION

FIG. 1 is a perspective view of a manifold gauge set showing our new design.

FIG. 2 is a front elevational view thereof.

FIG. 3 is a rear elevational view thereof.

FIG. 4 is a right side elevational view, the left side elevational view being a mirror image thereof.

FIG. 5 is a top plan view thereof; and,

FIG. 6 is a bottom plan view thereof.

The broken lines in the drawings are for illustrative purposes only and form no part of the claimed design.
